UNITED STATES PATENT OFFICE.

WILLIAM LEGGETT McCABE, OF SEATTLE, WASHINGTON.

ENDLESS CONVEYER.

SPECIFICATION forming part of Letters Patent No. 721,725, dated March 3, 1903.

Application filed November 21, 1901. Serial No. 83,206. (No model.)

To all whom it may concern:

Be it known that I, WILLIAM LEGGETT McCABE, a citizen of the United States, residing at Seattle, in the county of King and State of Washington, have invented certain new and useful Improvements in Endless Conveyers; and I do hereby declare the following to be a full, clear, and exact description of the invention, such as will enable others skilled in the art to which it appertains to make and use the same.

This invention relates to improvements in endless conveyers, and more particularly to the portable type.

15 The object in view is the provision of a strong, durable, conveniently-formed framework inclosing suitable power mechanism and supporting an endless conveyer-belt operated thereby, whereby the conveyer may be 20 transferred from place to place and readily positioned for operation with the expenditure of a minimum of time and labor.

With this and other objects in view the invention consists of certain novel constructions, combinations, and arrangements of parts, as will be hereinafter fully described and claimed.

In the accompanying drawings, Figure 1 represents a view in side elevation of a portable 30 conveyer embodying the features of my present invention. Figs. 2, 3, and 4 represent enlarged fragmentary views, in side elevation, of the same, the three figures together completing the entire length of the conveyer. Fig. 5 represents detail transverse sections through 35 portions of the frame-rails; Fig. 6, a view in top plan of the power-transmitting pulleys and surrounding parts, and Fig. 7 represents an end elevation of the conveyer. Fig. 8 represents an enlarged detail fragmentary view 40 of the cleaning-brush.

In the art to which my invention relates it has been found desirable to provide a conveyer adapted to be positioned close to the 45 base upon which the articles rest which are to be conveyed; and in order to produce such a structure I have provided, as seen in the drawings, a conveyer, as 1, having one end beveled, as at 2, on its under face, producing 50 a comparatively sharp nose, as 3, the opposite end, as at 4, being preferably compara-

tively wide, but rounded at the corners, as at 5 5.

The framework of conveyer 1 is composed of two upper parallel T-rails, as 6 6, and similar lower rails, as 7 7, said rails being spaced apart and connected laterally by cross-braces, as 8 8, in any suitable number and arrangement. Suitable diagonal braces, as 9 9, preferably angle-irons, connect each of the upper T-rails with its respective lower rail, whereby a rigid framework is formed. At each end of the framework is rotatably mounted a carrier-pulley, and transversely of the rails 6 and mounted thereupon are arranged any suitable number of intermediate supporting-rollers, as 10 10, carrying an endless belt, as 11, which belt passes over said supporting-rollers, the end pulleys, and is supported above the lower rails 7 by supporting-rollers, as 12 12, arranged upon said rails 7, similarly to rollers 10 upon rail 6, and in any suitable number, but preferably comparatively few.

The carrier-pulley, as 13, at the large end 4 of the framework is preferably of comparatively great diameter and is provided with a shaft, as 14, upon which it rotates, said shaft being preferably supported in slide-bearings, as 15, each slidably held between the lower face of its respective rail 6 and a suitable rail, as 17, arranged parallel to said rail 6 and spaced therefrom. A suitable bolt, as 18, is preferably rotatably secured to bearing 15 and is threaded through a fixed brace, as 19, and provided near its outer end with an enlarged squared portion, as 20, designed to be grasped by a suitable tool for rotation, whereby pulley 13 may be moved back and forth and the tautness of belt 11 governed. It will be seen that this arrangement makes it possible to have pulley 13 comparatively large and only a comparatively small portion of its periphery project beyond the plane of the two upper rails 6.

The carrier-pulley, as 21, at the opposite end of the framework is comparatively small, having its shaft of movement, as 22, mounted in suitable slide-bearings, as 23, each of said bearings being slidably held between the upper face of its respective rail 6 and a rail, as 24, arranged parallel to and spaced above rail

6 and bent downwardly at the ends, as at 25 25, and secured to said rail, suitable auxiliary braces 26 being employed for strengthening purposes when desired. A bolt, as 27, is 15 rotatably secured to bearing 22 and is threaded through a fixed brace, as 28, and near the outer end of said bolt, as at 29, is provided an enlarged squared portion designed to receive an operating-tool for purposes of rotation, whereby pulley 21 may be moved back and forth and belt 11 tightened or loosened. It will be seen that by this belt-tightener in connection with the one at the opposite end just described the belt 11 may be bodily shifted 20 in a taut condition longitudinally of the framework for the length of the operating-bolts. It is also obvious that the particular arrangement of the rails 24 makes it possible that the greater portion of the periphery of 25 pulley 21 may extend above the plane of the upper rails 6, whereby belt 11 is held parallel to and above the said rails throughout the length of the conveyer.

Intermediate the length of belt 11 as it 25 passes over rollers 12, arranged in any suitable number, are preferably provided belt-tighteners, as 30 30, constructed similarly to the means governing pulleys 13 and 21, each of said tighteners being provided with a 30 roller, as 31, designed to retain belt 11 in contact with rollers 12.

At any suitable point within the framework of conveyer 1 is mounted a transversely-arranged shaft, as 32, provided with a fixed 35 pulley, as 33, carrying a belt 34, communicating with a suitable source of power, as motor 35, mounted within the framework of the conveyer. A second pulley, as 36, is fixed to shaft 32 and carries a belt, as 37, passed about 40 pulley 13 and moving in an annular groove formed therein beneath belt 11 for imparting motion to said pulley and belt.

Any suitable number of belt-tighteners, as 38, similar to tighteners 31 may be arranged 45 in the framework of the conveyer, and each is provided with a roller designed to rest upon and hold taut its respective belt, at least one of tighteners 38 being arranged to affect each of belts 34 and 37.

50 In practice I have found that foreign matter is liable to fall upon the lower portion of belt 11 and be conveyed to and past the carrier-pulleys thereof, whereby the belt is injured, and there is great liability of the 55 same being thrown off its pulleys. To obviate these and other serious results which might arise, I provide any suitable form of brush, as 39, arranged above said lower portion of belt 11 and pivoted, as at 40, so as to normally rest by weight in contact with the belt, whereby the said foreign matter will be removed by coming into contact with the brush. The pivots 40 are mounted in a pair of oppositely-arranged diagonal braces 9, 60 whereby said brush 39 is yieldingly retained in position, the said brush being preferably V-shaped, as illustrated in Fig. 8 of the draw-

ings, with the apex arranged centrally of the belt and extending in an opposite direction to the movement thereof for directing the 70 foreign matter in both directions to the sides of the belt.

In operation the fact that one end of the conveyer 1 is beveled, as at 2, is highly beneficial, for the reason that the conveyer may 75 be caused to rest upon this flat bevel, whereby a large bearing-surface is provided, and the opposite end of the conveyer is at the same time extended upwardly, while the lower end lies close to the base supporting the 80 articles to be conveyed. The operation of the conveyer is obvious from the foregoing disclosure, any suitable conveyer-hooks (not shown) being applied to belt 11, if desired.

Although I have specifically set forth one 85 particular embodiment of the present invention, yet I wish it understood that I do not care to limit myself to the precise form disclosed, but shall feel at liberty to deviate therefrom in all matters of detail within the 90 spirit and scope of my invention.

Having thus fully described my invention, what I claim as new, and desire to secure by Letters Patent, is—

1. In a portable conveyer, the combination 95 with a suitable framework, of an endless belt carried thereby, and a V-shaped brush pivotally supported in said framework in position for resting by weight upon the inner face of the return portion of said belt, substantially as described.

2. In a portable conveyer, the combination with a suitable framework, of an endless belt carried thereby, and a brush pivoted at one end to the framework and resting by weight 105 upon the inner face of the return portion of said belt, substantially as described.

3. A portable conveyer, comprising a framework formed of upper and lower parallel T-rails, spaced from each other, and angle-irons 110 forming cross-braces and connecting said parallel rails, the said lower rails leaving their parallelism with the upper rails near one end, but maintaining the same with relation to each other, and approaching said upper rails, 115 thus forming a beveled portion at one end of the frame, which bevel is designed to rest upon a base for supporting said framework, while the opposite end of the framework extends upwardly, a comparatively small pulley mounted in the beveled end of the framework, a comparatively large pulley mounted in the opposite end thereof, and an endless belt carried by said pulleys, the said pulleys being arranged in the framework in such 125 manner relative to each other that their peripheries project the same distance above the plane of the upper edge of the framework, substantially as described.

4. A portable, endless conveyer, comprising a suitable framework, having upper and lower rails and suitable cross-braces, a comparatively large carrier-pulley mounted with 130 in said framework near one end thereof, a

- shaft supporting said pulley in position, bearings supporting either end of said shaft, a rail parallel to the upper rail of the framework at either side of said pulley and spaced 5 from its respective rail beneath the same, each of said bearings being slidably mounted between one of the upper rails and its parallel rail, a brace connecting said rails, a bolt revolvably secured to said bearing and threaded through said brace, and means for facilitating rotation of said bolt, whereby said pulley may be adjusted back and forth, a comparatively small pulley arranged at the opposite end of said framework to that of the 15 large pulley, a shaft supporting the same, a rod spaced above and extending parallel to each of the upper rails, a bearing slidably secured between each upper rail and its respective parallel rod, each bearing revolvably 20 supporting one end of said shaft, a brace connecting each upper rail with its parallel rod, a bolt revolvably connected with each slide-bearing and threaded through its respective brace, and means for facilitating rotation of 25 said bolts, whereby said small pulley may be adjusted back and forth, an endless belt connecting said large and small pulleys the construction being such that simultaneous adjustment of both of said pulleys will move said belt longitudinally of said framework, 30 and means for imparting motion to said large pulley, substantially as described.
5. In a portable conveyer, the combination with a suitable framework, of pulleys at either end thereof, an endless belt carried 35 thereby and having its return half moving within said framework, and a brush pivoted to said framework and resting by weight upon said return portion of the belt, substantially as described. 40
6. In a portable conveyer, the combination with a suitable framework, of an endless belt carried thereby, and a V-shaped brush pivotally supported in said framework in position for resting by weight upon the inner 45 face of the return portion of said belt with the apex of the brush extending in an opposite direction to that of the movement of the belt, substantially as described.

In testimony whereof I hereunto affix my 50 signature in presence of two witnesses.

WILLIAM LEGGETT MCCABE.
